LIFTING DEVICE FOR ARTICLES

John J. Mueller and Charles P. Meyer,
Pelham, N. Y.

Application March 12, 1943, Serial No. 478,892

1 Claim. (Cl. 294—103)

This invention relates to a device for lifting articles in such a way that the articles are clamped by the device when lifting force is applied to lift them, so that the danger of the articles accidentally falling is obviated. Also, when the articles have been removed by the device to the desired place, such, for example, as to a car by which they are to be transferred, the lifting device is automatically disconnected from them when they are lowered into place.

The device is particularly useful for the purpose of handling coils of strip steel, but it is to be understood that the invention is not restricted to this particular use as it may be used for different sorts of articles that have surfaces or portions available that may be clamped between portions of the device one of which is movable with respect to the other so as to serve as a clamp or holding portion.

The invention may be understood from the description in connection with the accompanying drawing, in which:

Fig. 1 is a side view of an illustrative embodiment of the invention;

Fig. 2 is a view at right angles to Fig. 1;

Fig. 3 is a section along the line *a—a* of Fig. 1; and

Fig. 4 is a section along the line *b—b* of Fig. 1.

In the drawing, reference character 1 indicates a metal bar with notches 2 along one edge thereof. It is provided with a bolt 3 near one end by which it is pivoted between the spaced curved portions 4 of an arm 5. Holes 6 are provided along the arm 5 through which a bolt 7 passes for adjustment of a link 8 at different places along this arm, thus providing different leverages. The link 8 is connected to the bolt 7 and carries a ring 9 to which a hook 10 at the end of the chain 11 may be attached.

A metal U-shaped member 15 is slidable on the bar 1 and the ends thereof are connected by straps 16 and bolts 17 and 18 to the extending portion 19 of the bifurcation 4 of the arm 5.

A holding member 20 is adjustable along the

bar 1. It is provided with a diagonal opening or passageway 21 shown by dotted lines in Fig. 1 so that the bar 1 can pass therethrough. The extent of this opening is such that when the member 20 is at right angles to the bar 1, as shown in Fig. 1, the corner 22 catches in a notch 2 of the bar 1, thus preventing it from moving to the right as seen in this figure. However, this holding member 20 can be adjustable along the bar 1 by first turning the holding member clockwise and sliding it in either direction.

The operation is as follows:

The member 20 is adjusted along the bar 1 in accordance with the size of the article that is to be clamped between the members 15 and 20. The portion 22 in any notch 2 holds the member 20 in adjusted position so that pressure may be applied along the edge 24 without moving this member along the bar 1. The device is then brought to the object that is to be handled so that a graspable portion of it is between the extending portions of the members 15 and 20. The lever 4 is then turned on pivot 3 by applying force to the chain 11, whereupon the slidable member 15 is moved along the bar 1 towards the member 20, thus clamping the object. As more force is applied to the chain 11 the clamping of the object between members 15 and 20 is automatically increased proportionately to the weight of the object, so that the danger of heavy objects accidentally slipping out is no greater than when lighter objects are handled.

What is claimed is:

A lifting device, comprising a bar, a lever pivoted to said bar, a holding member and a clamping member each being supported on and slidable on said bar, said clamping member being connected to said lever and said holding member being rectangularly shaped and having an opening therethrough with upper and lower inner surfaces of said opening at an angle to its edges.
